UNITED STATES PATENT OFFICE.

CARL W. RUSSELL, OF YOUNGSTOWN, OHIO.

SPEED REGULATOR FOR AUTOMOBILES.

Application filed January 12, 1922. Serial No. 528,657.

To all whom it may concern:

Be it known that CARL W. RUSSELL, citizen of the United States of America, residing at Youngstown, in the county of Mahoning and State of Ohio, has invented certain new and useful Improvements in Speed Regulators for Automobiles, of which the following is a specification.

This invention relates to speed regulators 10 for automobiles.

The principal object is to provide a device which may be set and locked and still allow a desired range in the amount of gas to enter the manifold of an internal combustion engine.

A further object is to provide a suction control in moving a rotatable disc over a circular member, each having a plurality of openings positioned so as to register when 20 the rotatable disc is caused to partially rotate.

A further object is to provide an arm extending from the rotatable disc and functioning in a seat in a piston which is caused to move back or forward by means of a 25 suction caused by the suction in the manifold.

A still further object is to provide a locking means whereby the rotatable disc may be set so as to admit a determined amount of 30 gas, and which cannot be changed without access to the key.

Many city ordinances and State laws limit the speed of automobiles. Where an employer has a number of machines it is 35 difficult for him to prevent speeding by the drivers. This often results in accidents and damage suits. This invention will protect owners of such machines against unnecessary damage.

With these and other objects in view the invention consists in the novel arrangement and construction of parts which will be hereinafter more fully described and claimed.

In the drawings Figure 1 is a detail view 45 showing the operating button as installed on an instrument board of machine.

Figure 2 is a side view of the entire device when installed on a machine.

Figure 3 is a detail view showing valve 50 and connecting parts which is secured to manifold.

Figure 4 is a detail view in section of valve shown in Figure 3.

Figure 5 is a detail sectional view of the

valve as shown in Figure 3, at right angles 55 to the section shown in Fig. 4.

Figure 6 is a vertical sectional view on the line 2—2 of Figure 2.

Figure 7 is a sectional vertical view of the device shown in section in Figure 6 and 60 is taken on a line 3—3 of Figure 6.

By referring to Figure 2 it will be seen that I have provided a casing 1, which is inserted in place of an ordinary gasket between a carburetor 2 and a manifold 3, and 65 is secured by means of bolts 4 which pass through the slots 5 of the casing 1.

By referring to Figures 6 and 7 it will be seen this casing 1 is provided with a disc shaped portion 6, provided with a plurality of openings 7. Mounted upon a pivot 8 is a rotatable disc 9 provided with a plurality of openings 10 registering with the openings 7 of the disc shaped member 9. This rotatable disc 9 is provided with an arm 75 11 seated in recess 12 of a piston 13 which is movable within a piston chamber 14. At the ends of the piston chamber 14 I have provided adjustable stops 15 and 16. The adjustable stop 16 is secured by means of 80 a plug 17 which is larger in diameter than the piston 13 and is placed in position after the piston 13 has been placed in the piston chamber 14.

At the ends of the piston chamber 14 85 are outlets 18 and 19. In these outlets are connected tubes 20 and 21 which lead to opposite sides of a three-way-valve 22.

This three-way-valve 22 is caused to move by means of a rod 23, one end of which is 90 attached to a slideable button 24 mounted upon an instrument board 25. The other end of said rod 23 is attached to an arm 26, which is in turn secured near the circumference of the valve 22. By manipulating this rod 23 the valve may be turned so as to connect up with either the tube 20 or 21, thereby producing a partial vacuum in either end of the piston chamber 14, which in turn causes the piston to move to the right or 100 left as desired. For instance, if the driver wishes to feed the maximum amount of gas provided by this device, he would move the three-way-valve 22 so as to cause a suction in the tube 21, thereby pulling the rotatable 105 disc 9 so that the openings 10 are directly over the openings 7. When it is desired to use the minimum amount of gas the valve

22 would be manipulated so as to cause a suction in the tube 20, thereby reversing the action of the piston 13 and connecting parts.

5 It will be seen by referring to Figure 6 that I have provided notches 27, into which may be forced a key plunger 28 by means of a key 29, thereby locking the rotatable disc 9 as desired.

10 By referring to Figures 2, 3 and 5 it will be seen the three-way-valve 22 is provided with a connection 30, which connects with the upper portion of the manifold 3.

What I claim is:

15 1. In a device of the class described, a casing secured between a carburetor and the lower end of a manifold, a disc shaped portion centrally located in said casing, a plurality of openings in said disc, a revolvable disc located against said disc member, a plurality of openings in said revolvable disc, a 20 downwardly extending arm formed on said revolvable disc, a chamber formed in the

lower portion of said casing, a piston located within said chamber, a seat formed in 25 said piston for the seating of said downwardly extending arm, stops at each end of said chamber, outlets at each end of said chamber, tubes connected to said outlet, the other end of said tubes connecting to a three-way-valve, a connection from said three-way-valve to an upper portion of a manifold, substantially as described for the purpose set forth.

2. In a device of the class described, a 35 rotatable disc positioned over a disc shaped member, each having a plurality of openings, a plurality of notches in said rotatable disc, a key plunger functioning in said notches, substantially as described for the 40 purpose set forth.

In testimony whereof I affix my signature.

CARL W. RUSSELL.
